KELLY-SPRINGFIELD TIRE CO., OF NEW YORK, N. Y.

MIXING-MACHINE.

1,344,541.

Specification of Letters Patent. Patented June 22, 1920.

Application filed November 8, 1919. Serial No. 336,638.

To all whom it may concern:

Be it known that we, JOSEPH D. LACROIX, a citizen of the United States, residing at 50 West street, Akron, Summit county, 5 Ohio, and AUGUST H. PETERSEN, a citizen of the United States, residing at No. 64 South Broadway, city of Akron, Summit county, Ohio, have invented a new and useful Mixing-Machine, of which the following is 10 a specification.

Our invention relates to a machine for mixing powder, plastic, or granulated materials, or mixing powder materials with plastic materials, such as lamp-black with unvulcanized rubber and similar substances, 15 particularly mixing impalpable powders that readily fly about, pollute the atmosphere and are wasted in the mixing operation. We eliminate these and other objectionable features attending the mixing of powdered materials by inclosing the entire mixing apparatus in a dust proof,—practically an air tight chamber during the operation. The machine consists of a revolving 20 dust proof barrel shaped cylinder or tumbler, equipped internally with conveyer pockets or ribs and inclosing a pair of separate and independent water cooled revolving cylinders or rollers which revolve in 25 opposite direction, and in conjunction with the revolution of the tumbler casing and conveyer pockets. This arrangement produces a thorough mixing of powders and a thorough kneading of plastic material with- 30 out waste and resulting in a great saving of expense and the absence of the unsanitary results usually attending the working up of deleterious or impalpable powders such as the coloring matter used in rubber 35 compounds and similar substances. The mechanism of the machine is shown in the accompanying drawings of which—

Figure 1, is an outside view of one side of the entire machine, the driving power 45 omitted. Fig. 2, is a plan view of the machine, driving power omitted, Fig. 3 is a cross sectional view taken substantially on line $a-a$ of Fig. 2. Fig. 4, is a vertical sectional view taken substantially on line 50 $b-b$ of Fig. 3. Like numerals refer to like parts in all figures.

The barrel shaped chamber or tumbler 4, is equipped with internal conveyer pockets 5—5 which help to keep the contents of the 55 chamber in constantly changing relations.

A large part of the upper half of the cylinder constitutes a door 4^a which opens on hinge 6, and is secured by clasp 7. This door when closed forms a part of the chamber casing. The inside of the ends or edges 60 of the cylinder portion of the chamber revolve around and on the edges of the circular stationary ends 8, as shown at the point 9. The outer edges of the cylinder portion are furnished with gearings 10, 65 which engage with gear wheels 11—11^a, which last mentioned wheels are rigidly mounted on the counter shaft 12, and which counter shaft with the gear wheels 11—11^a is operated through spur wheel 13 controlled by clutch 13^a, which spur wheel 13 is 70 rotatably mounted on driving shaft 14. Said driving shaft 14 being rotatably mounted in bearing 15. On driving shaft 14 is rigidly mounted belt wheel 16, through 75 which power is applied to operate the entire machine. On driving shaft 14 is also rotatably mounted spur wheel 17 controlled by clutch 17^a, which spur wheel 17 engages with and operates large gear wheel 18, and 80 which large gear wheel is rigidly mounted on shaft 19 which is an extension of one end of mixing roller 20. The opposite end of mixing roller 20 also has an extension in the form of a shaft 19^a on which is rigidly 85 mounted gear wheel 21, and this last mentioned gear wheel engages with a somewhat larger gear wheel 22 (best shown in Fig. 2), which gear wheel 22 is rigidly mounted on the shaft end 23 of the other mixing 90 roller 20^a.

It will thus be seen that the driving shaft 14, and the spur wheel 13, drives gear wheel 11, and its companion gear wheel 11^a, both on the counter shaft 12, and these in turn 95 revolve the barrel shaped chamber which is equipped with gearings 10 on the outside of each end; at the same time spur wheel 17 drives the large gear wheel 18 which is rigidly mounted on shaft end 19 of mixing 100 roller 20; mixing roller 20 drives its companion mixing roller 20^a through gear wheel 22 which last mentioned wheel is rigidly mounted on the shaft end 23 of mixing 105 roller 20^a.

The function of gear wheels 24 which synchronize with gearing 10 is to prevent vibration and help steady the revolving cylinder; rollers 25 mounted on shafts 26 also perform the same function. 110

Chamber heads 8 are rigidly secured to the bearings 27 by tie plates 28, and in the bearings 27 are revolvably mounted roller shaft ends 19—19^a, 23 and 23^a, and the bearings 27 and 29 are rigidly mounted on a suitable bed piece.

The shaft ends 19^a and 23 have central conduits or bores 30, 30^a connected with water conducting pipes, 31, 31^a through which conduits water is forced into roller chambers 32, 32^a. Within said conduits are located waste water pipes 33, 33^a of considerable smaller diameter than the conduits; cold water is forced into the roller chambers through the conduits and the waste water pipes 33, 33^a carry off the same serving to keep a body of cold water in the roller chambers at all times, and thus prevent over heating of the mixing rollers.

20 The plates 34, 34^a tend to prevent the material from being pressed out at the ends of the rollers.

On the edge of the door we attach a suitable packing 35, and it will be understood that suitable packings may be used elsewhere to make the mixing cylinder dust tight.

Claims.

1. In a machine of the character described, a closed mixing chamber having stationary ends and a body casing adapted to revolve around said ends in contact therewith, associated mixing mechanism within said chamber, means to revolve said body casing and to operate said associated mechanism.

2. In a machine of the character described, a closed mixing chamber having circular stationary ends, a body casing adapted to revolve around said ends, in contact therewith, independent mixing rollers adapted to revolve within said mixing chamber and means to revolve said body casing and said mixing rollers.

45 3. In a machine of the character described, a closed mixing chamber having circular stationary ends, a body casing adapted to revolve around and upon said circular ends and around independent revolute mixing rollers, independent hollow mixing rollers adapted to revolve within said mixing chamber, and means to revolve said body casing and said mixing rollers.

4. In a machine of the character described, a closed mixing chamber having circular stationary ends, a body casing adapted to revolve around and upon said circular ends, and around mixing rollers, said body casing having a plurality of internal projections, separate hollow mixing rollers adapted to revolve within said mixing chamber, and means to revolve said body casing and mixing rollers.

5. In a machine of the character described a cylindrical mixing chamber hav-

ing stationary ends and a body part adapted to revolve around separate revolving mixing rollers; said body part having on the inside thereof a plurality of conveyer cups attached thereto, separate mixing rollers adapted to revolve within said mixing chamber and means to revolve said body part and mixing rollers.

6. In a machine of the character described, a mixing chamber having stationary ends and a revolvable body part inclosing independent hollow revolvable mixing rollers; said body part having on the inside thereof a plurality of conveyer cups and a portion of said mixing chamber adapted to open and close; separate hollow mixing rollers adapted to revolve within said mixing chamber and means to revolve said body part and said mixing rollers.

7. In a machine of the character described, a mixing chamber having stationary ends and a revolvable body part inclosing independent revolvable mixing rollers; said body part having a plurality of internal conveyer cups attached thereto. Hollow independent mixing rollers adapted to revolve within said mixing chamber and means to revolve said body part and mixing rollers.

8. In a machine of the character described a mixing chamber having stationary ends and a revolvable body part inclosing independent hollow revolvable mixing rollers; said body part having a plurality of conveyer cups attached to the inside thereof and a portion of said mixing chamber adapted to open and close as a door, and means to revolve said body part and mixing rollers.

9. In a machine of the character described, a closed mixing chamber having circular stationary ends, a revolvable body casing, the inner surface of said body casing equipped with a plurality of projecting flanges, independent hollow mixing rollers adapted to revolve within said mixing chamber, said rollers having a hollow central portion adapted to hold a body of water and means to revolve said body casing and mixing rollers.

10. In a machine of the character described, a mixing chamber having a stationary portion and a revolvable portion, the interior surface of said revolvable portion having a plurality of conveyer cups attached thereto; independent mixing rollers adapted to revolve within said mixing chamber and having hollow central portions and an orifice for the admission of water; waste water pipes connected with said central portions and means to revolve the revolvable portion of said mixing chamber and the mixing rollers.

11. In a machine of the character described, a revolvable mixing tumbler

equipped with gearings on its outer surface, and having stationary end. The revoluble portion being equipped on the inside with a plurality of conveyer cups attached thereto, 5 and adapted to revolve around the stationary ends; separate revoluble mixing rollers adapted to revolve within said tumbler, and having central chambers adapted to hold water; waste water pipes connected with 10 said central chambers and means for conducting currents of water into and out of said central chambers, and means to revolve said tumbler and said mixing rollers.

12. In a machine of the character described a cylindrical revoluble mixing tumbler equipped with gearings on its outer surface and having stationary ends. Said

tumbler having a plurality of internal conveyer cups attached thereto; separate revoluble mixing rollers adapted to revolve within said tumbler and having central hollow portions adapted to hold water, conduits connecting said hollow portions with a water supply system; waste water pipes located within said conduits and of smaller 20 external diameter than the internal diameter of said conduits; means to force a supply of water into and out of said central chambers, and means to revolve said tumbler and mixing rollers.

JOSEPH D. LACROIX.
AUGUST H. PETERSEN.
